GARBAGE TRUCK BODY

Edward T. Newell, Portland, Oreg.

Application February 15, 1951, Serial No. 14,216

Term of patent 14 years

(Cl. D14—3)

To all whom it may concern:

Be it known that I, Edward T. Newell, a citizen of the United States, residing at Portland, in the county of Multnomah and State of Oregon, have invented a new, original, and ornamental Design for Garbage Truck Bodies, of which the following is a specification, reference being had to the accompanying drawing, forming part thereof.

Figure 1 is a side perspective view of a garbage truck body, showing my new design.

Figure 2 is a perspective rear end view of Figure 1.

Figure 3 is a plan view, showing my new design.

Figure 4 is a side view, with the loading doors open.

Figure 5 is a front view of the body.

The dotted lines shown in the drawing are for illustrative purposes only.

I claim:

The ornamental design for a garbage truck body, as shown and described.

EDWARD T. NEWELL.
